Primary Examiner — Steven J Czyz

(57) CLAIM

The ornamental design for a box for dispensing medicine, as shown and described.

DESCRIPTION

FIG. 1 is a front, top and right-side perspective view of the box for dispensing medicine showing my new design; FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a rear, bottom and left-side perspective view thereof;

FIG. 9 is a perspective view thereof, shown in a position of use;

FIG. 10 is another perspective view thereof, shown in a position of use; and,

FIG. 11 is another perspective view thereof, shown in a position of use.

The broken lines throughout the drawing figures depict portions of the box for dispensing medicine that form no part of the claimed design.

1 Claim, 11 Drawing Sheets
